(57) **CLAIM**

I claim the ornamental design for a carbide tip for grinding teeth, as shown and described.

DESCRIPTION

FIG. 1 shows the front perspective view of a carbide tip for grinding teeth showing my new design,

FIG. 2 shows the rear perspective view thereof,

FIG. 3 shows the top view of the carbide tip,

FIG. 4 shows the front view of the carbide tip,

FIG. 5 shows the right side view of the carbide tip,

FIG. 6 shows the bottom view of the carbide tip,

FIG. 7 shows the left view of the carbide tip; and,

FIG. 8 shows a rear view of the carbide tip.
